ELECTRON DISCHARGE DEVICE

Arthur L. Samuel, Orange, N. J., assignor to Bell Telephone Laboratories, Incorporated, New York, N. Y., a corporation of New York

Application October 27, 1933, Serial No. 695,497

16 Claims. (Cl. 250—27.5)

This invention relates to electron discharge devices and more particularly to such devices adapted for the generation of ultra-high frequency oscillations.

5 In one form of electron discharge devices commonly known as Barkhausen oscillators, the current to the output electrode, which may be in the form of a grid and is at a positive potential relative to the cathode, comprises a constant component due to electrons which flow to this electrode directly from the cathode, and a variable component due to electrons which flow to the electrode after passing between the wires thereof and into the region between this electrode and a 10 third electrode, which may be at zero or at a small negative potential, on the side of this electrode remote from the cathode. It is desirable for efficient operation, that the variable component be a large part of the total current to the output electrode.

20 One object of this invention is to reduce the constant component of the current to the output electrode in electron discharge devices and thereby to increase the efficiency of such devices.

25 In one embodiment of this invention, an electron discharge device of the Barkhausen oscillator type comprises a cathode, an output electrode including a plurality of parallel wires disposed in a cylindrical boundary about the cathode, and a third electrode encircling the cathode and the output electrode.

30 In accordance with a feature of this invention, the portions of the wires of the output electrode directed toward the cathode and toward the third electrode are coated with an insulating material, for example, beryllium oxide, so that no electrons can flow in a linear path from the cathode to the output electrode wires, or from the third electrode to the output electrode wires, and 35 the constant component of the current to the output electrode is thereby reduced.

40 The invention and the features thereof will be understood more clearly and fully from the following detailed description with reference to the accompanying drawing in which:

45 Fig. 1 is a perspective view of an electron discharge device of the general type comprehended by this invention, portions of the enclosing vessel being broken away to show the internal structure more clearly;

50 Fig. 2 is an enlarged detail view in longitudinal cross-section of the electrode structure of the device shown in Fig. 1; and

55 Fig. 3 is an enlarged view of the cathode and output electrode as viewed from line 3—3 in Fig.

2, showing clearly the position of the insulating coating on the wires constituting the output electrode.

5 Referring to the drawing, the device shown is of the type adapted for the generation of ultra-high frequency oscillations and commonly known as a Barkhausen oscillator. It comprises an evacuated enclosing vessel 10 having a reentrant stem 11 which terminates in a press 12. A pair of bent or substantially inverted L-shaped wires 13 are embedded at one end in the press 12 and have secured thereto a pair of parallel resilient metallic rods or members 14. A single linear filament 15 of tantalum, tungsten or other material having good electron emitting characteristics, is secured at its end to the rods 14 and serves as the cathode of the device. The heating current for the cathode may be supplied through leading-in conductors 16 connected to the wires 13.

10 A bent wire 17 is embedded at one end in the press 12 and at the other end in an insulating bead 18, the wire 17 being disposed in a plane at substantially right angles to the plane of the wires 13. A metallic ribbon 19 is secured at one 15 end to a rod 20 embedded in the insulating bead 18, and at the other end to another rod 21 sealed in the end of the enclosing vessel as shown at 22. The ribbon 19 is preferably flexible and bowed to 20 allow longitudinal expansion and contraction of the rods 20 and 21 with temperature variations.

25 A cylindrical electrode 23 having a longitudinal flange 24 is supported from rigid L-shaped wires 25 secured to the rod 20 and to the flange 24. A reinforcing rod or wire 60 may be secured on the 30 flange. The electrode 23 may be of sheet molybdenum, the surfaces of which are roughened by carborundum blasting to increase the heat radiation therefrom, and is disposed about and coaxially with the filament 15.

35 A bent wire 26 is embedded at one end in the press 12 and carries an insulating bead 27. A bowed, flexible metallic ribbon 28, similar to the ribbon 19, is connected between a rod 29 embedded in the insulating bead 27 and a rod 30 40 sealed in the enclosing vessel 10 as shown at 31. A U-shaped wire or support 32 is secured to the rod 29 and is rigidly held in position by braces or rods 33 secured thereto and to the rod 29.

45 An output or grid electrode assembly is carried by the support 32 and comprises a pair of cylindrical metallic collars 34 connected to the arms of the support 32 by short, rigid wires 35, only one of which is shown in Fig. 1. The collars 34 encircle the ends of the filament 15 and have se- 50 55

cured thereto a plurality of equally spaced parallel wires 38, which may be of tungsten and are disposed parallel to the filament 15 and arranged in a cylindrical boundary coaxial with the filament.

In order to dissipate the heat from the grid or output electrode, a pair of fins or annular discs 37 of relatively large area, and of a material having good heat radiating characteristics, for example, molybdenum or nickel roughened by carbonium blasting, are disposed adjacent the ends of the grid wires 38 and are thermally coupled thereto. The discs 37 may be disposed in contact with the collars 34 and may be connected to the collars by a plurality of bent wires 39 of good thermal conductivity.

The end portions of the filament 15 within the collars 34 may be surrounded by tubular sleeves 39 of nickel or the like, secured to the rods 14 by tabs 40. The sleeves 39 serve to substantially prevent the flow of electrons to the collars and thereby confine the electrons emitted from the filament 15 to paths embracing the wires 38 of the output electrode.

In utilizing the device described, for the generation of ultra-high frequency oscillations, the grid or output electrode is operated at a relatively high positive potential with respect to the filament or cathode 15, and the outer electrode 23 is operated at zero potential or at a low negative potential with respect to the filament or cathode.

Although the exact field conditions and electron action in the device during operation are not known with certainty, it is known that electrons emitted from the filament or cathode travel outwardly from the filament or cathode under the influence of a positive potential on the grid or output electrode. Some of the electrons pass directly to the wires 38 and impinge thereupon, while other of the electrons pass between the wires 38 into the region between the wires and the outer electrode 23. Some of the latter electrons may impinge upon the electrode 23, and, since this electrode is at a zero or at a negative potential, are repelled from the electrode and attracted to the wires 38 and adsorbed thereby. Other of the electrons may be sufficiently retarded by the positive potential on the output electrode, after they have passed into the region between the output electrode and the outer electrode 23, and may oscillate between the wires 38 before finally impinging upon and being adsorbed by the wires 38.

From this it will be apparent, and experiments have substantiated the result, that the output current comprises at least two components, one of which is substantially constant and results from the electrons which flow directly from the filament or cathode 15 to the wires 38 and of the electrons which pass to the wires 38 after being reflected from the electrode 23, and a variable or oscillatory component resulting from the electrons which oscillate between the wires 38 before finally impinging upon the wires and being adsorbed thereby. For efficient operation, it is desirable that the constant component of the output current be small and that the variable or oscillatory component of the output current be large. In accordance with this invention, a small constant component of the output current is insured by providing means substantially preventing the flow of electrons directly from the filament or cathode 15 to the wires 38 and directly from the outer electrode 23 to the wires. This insures the passage of a large number of the electrons 75 one or more times between the wires 38 whereby

a large variable or oscillating component in the output current is obtained.

In a specific embodiment of the invention, the surfaces of the wires 38 in radial alignment with the filament or cathode 15 and with the outer electrode 23 are covered with insulating coatings 41 which prevent the adsorption by the wires 38 of those electrons which impinge upon the insulating coating and insure the passage of these electrons into the region between the wires 38. The coatings 41 are preferably of a material which is stable at the temperatures extant in the device during operation and which will retain its insulating properties for an appreciable time. Beryllium oxide, for example has been found to be satisfactory, although other materials which meet the requirements set forth above may be used.

Although the invention has been described as embodied in a specific structure, it will be understood, of course, that it may be embodied equally well in structures of other designs without departing from the scope and spirit of the invention as defined in the appended claims. For example, the output electrode may comprise a plurality of circular wires encircling the cathode or it may comprise a helical wire disposed about the cathode and coaxial therewith. Portions of the circular wires or of the helical wire directed toward the cathode and toward the outer electrode may be coated with an insulating material substantially the same as described in the specific embodiment of the invention shown in the drawing.

What is claimed is:

1. An electron discharge device comprising an electron emitting electrode, an electron receiving electrode in cooperative relation with said first electrode, said electrodes being disposed one within the other, and insulating means intermediate all aligned portions of said electrodes for preventing the flow of electrons in a rectilinear path between said electrodes.

2. An electron discharge device comprising an electron emitting electrode, an electron receiving electrode in juxtaposition to said first electrode, and an insulating coating on all portions of said electron receiving electrode in alignment with said first electrode.

3. An electron discharge device comprising a cathode capable of emitting electrons when heated, an output electrode in cooperative relation with said cathode, and a coating of beryllium oxide on portions of said output electrode directed toward said cathode.

4. A Barkhausen oscillator comprising a cathode, an electrode in juxtaposition to said cathode, an electron receiving electrode intermediate said cathode and said first electrode, and insulating means adjacent said electron receiving electrode for preventing the flow of electrons thereto in a rectilinear path from said cathode.

5. An electron discharge device comprising an electron emitting electrode, an electron receiving electrode, a third electrode outside of said electron receiving electrode, and an insulating shield intermediate said electron emitting electrode and all portions of said electron receiving electrode in alignment with said electron emitting electrode.

6. An electron discharge device comprising a cathode, an electrode in juxtaposition to said cathode, a grid electrode having a plurality of spaced wires intermediate said cathode and said electrode, and an insulating coating on all the portions of said wires directed toward said cathode.

7. An electron discharge device comprising a

- cathode, an electrode in juxtaposition to said cathode, a grid electrode having a plurality of spaced wires intermediate said cathode and said electrode, and a coating of beryllium oxide on the portions of said wires directed toward said cathode.
8. An electron discharge device comprising an output electrode, a cathode on one side of said output electrode, an electrode on the opposite side of said output electrode, insulating means intermediate said cathode and said output electrode for preventing the flow of electrons in a rectilinear path from said cathode to any portions of said output electrode in alignment with said cathode, and additional insulating means between all aligned portions of said output electrode and said second electrode.
9. An electron discharge device comprising a cathode, an electrode in juxtaposition to said cathode, an output electrode intermediate said cathode and said electrode, and insulating shielding means intermediate juxtaposed surfaces of said cathode and said output electrode and of said first electrode and said output electrode, said means being disposed to prevent the flow of any electrons in a linear path from said cathode and said first electrode to said output electrode.
10. An electron discharge device comprising an output electrode, a cathode on one side of said output electrode, an electrode on the opposite side of said output electrode, and insulating coatings on all portions of said output electrode in alignment with said cathode and said second electrode.
11. An electron discharge device comprising a cathode, an outer electrode in cooperative relation with said cathode, a perforate electrode intermediate said cathode and said outer electrode, and coatings of beryllium oxide on portions only of said perforate electrode directed toward said cathode and said outer electrode.
12. An electron discharge device comprising a cathode, an electrode including a plurality of wires mounted in a cylindrical boundary about said cathode, and an insulating coating on portions only of said wires in radial alignment with said cathode. 5
13. An electron discharge device comprising a linear cathode, an electrode including a plurality of wires disposed parallel to one another and to said cathode and mounted in a cylindrical boundary about said cathode, and insulating shielding means between aligned portions of said cathode and said wires. 10
14. An electron discharge device comprising a linear cathode, an output electrode including a plurality of wires disposed parallel to one another and to said cathode, and mounted in a cylindrical boundary about said cathode, and an insulating coating on portions only of said wires in radial alignment with said cathode. 15
15. An electron discharge device comprising a linear cathode, a cylindrical electrode encompassing said cathode and coaxial therewith, an electrode including a plurality of spaced wires disposed parallel to one another and to said cathode and mounted in a cylindrical boundary intermediate said cathode and said cylindrical electrode and coaxial therewith, and insulating shielding means intermediate radially aligned portions of said wires and said cathode and 20 cylindrical electrode. 25
16. A Barkhausen oscillator comprising a linear cathode, an output electrode including a plurality of wires disposed parallel to one another and to said cathode and mounted in a cylindrical boundary coaxial with said cathode, a cylindrical electrode encompassing said cathode and said wires and coaxial with said cathode, and coatings of beryllium oxide on portions only of said wires in radial alignment with said cathode and said cylindrical electrode. 40

ARTHUR L. SAMUEL.

DISCLAIMER

2,000,990.—*Arthur L. Samuel, Orange, N. J. ELECTRON DISCHARGE DEVICE.*
Patent dated May 14, 1935. Disclaimer filed May 9, 1936, by the assignee,
Bell Telephone Laboratories, Incorporated.

Hereby enters this disclaimer to the subject-matter of claims 1, 4, 5, and 13 of
said Letters Patent, to wit:

Your petitioner disclaims from the scope of claim 1 any electron discharge
device as therein defined except such electron discharge device wherein the insulating
means is in close proximity to the electron receiving electrode and relatively remote
from the electron emitting electrode.

Your petitioner disclaims from the scope of claim 4 any Barkhausen oscillator
as therein defined except such Barkhausen oscillator wherein the insulating means is
immediately adjacent and in contact with the electron receiving electrode.

Your petitioner disclaims from the scope of claim 5 any electron discharge
device as therein defined except such electron discharge device wherein the insulating
shield is disposed in immediate proximity to the electron receiving electrode and is
carried thereby.

Your petitioner disclaims from the scope of claim 13 any electron discharge
device as therein defined except such electron discharge device wherein the insulating
shielding means is in close proximity to the wires of the electrode and is supported
thereby.
